TOBACCO POUCH

Victor F. Zahodiakin, New York, N. Y.

Application January 14, 1936, Serial No. 59,100

2 Claims. (Cl. 206—41)

This invention relates to pipe smoking and is particularly directed to a device for cleaning a pipe, which device is associated with a tobacco pouch.

It is a recognized fact that a pipe must be cleaned after each smoke, due to the accumulation of ashes in the bottom of the pipe which clog the passageway most of the time. This cleaning is accomplished by striking the bowl of the pipe against some solid object for the purpose of dislodging or knocking the caked ashes from the pipe. This, of course, results in frequent breakage of pipes, and, where the pipes are expensive, is apt to be costly.

Also, this means for cleaning a pipe is rather ineffective; that is to say, the ashes are not dislodged and the clogged condition continues to exist.

It is the object of the present invention to provide a pipe cleaning instrumentality readily adapted for association with a tobacco pouch, which instrumentality is readily contained within the pouch and is conveniently accessible for use at the time of refilling the pipe. In other words, the present invention provides for greater convenience, as well as effectiveness, in the operation of cleaning the pipe.

It is a further object of this invention to provide a tobacco pouch which includes a compartment for the tobacco and a sheath for the cleaning instrumentality, in relation to which sheath the cleaning device is readily attached in position against accidental displacement.

Other objects and certain advantages will be more fully apparent from a description of the accompanying drawing, in which:

Figure 1 is a side view of a pouch incorporating the present improvements.

Figure 2 is a sectional view taken on line 2—2, Figure 1, illustrating the details of the compartment or sheath for containing the cleaning instrumentality.

Figure 3 is a sectional view taken on line 3—3, further detailing the structure of Figure 2.

Figure 4 is an edge view of the cleaning device.

Figure 5 is a side view thereof.

Referring to the drawing, the tobacco pouch is indicated at 10. This pouch may be formed of any material suitable for this purpose, such as leather, cloth, etc. The pouch includes two compartments, indicated at 11 and 12 respectively. The pouch structure is subdivided to

provide these compartments or receptacles by means of stitching 13, extending from the top to the bottom edge of the pouch. This stitching is disposed toward one end edge thereof so as to provide an elongated or narrow compartment or sheath which is open at the top, as at 14. This sheath or receptacle 11 is adapted to receive a blade 15. The blade is formed of flat stock and has its operating end curved to a point. It is attached to the pouch by means of a flexible strap or thong 16, laced through a slot 17 in the end of the blade.

The ends of the strap are secured together and incorporate the female element 18 of a snap fastener device 19. Thus the thong or strap is in the form of a loop. The complementary part or male element 20 of the snap fastener device is secured to the side wall of the sheath adjacent the upper end thereof. Accordingly, the cleaning blade is readily fastened in position so that it does not accidentally become detached from the pouch, yet is conveniently accessible and removable when the smoker desires to use the same. The tobacco receptacle portion of the pouch is readily closed by means of the conventional zipper shown at 22.

By means of the present improvement all of the difficulties of performing the pipe cleaning operation are eliminated. A very convenient and efficient cleaning device is provided in conjunction with the tobacco supply providing the means for cleaning the pipe. Accessibility and location are afforded under the most convenient conditions possible for the reason that the smoker naturally thinks of cleaning his pipe just before he fills it. With the means at hand, as provided herein, he has no trouble in efficiently eliminating any clogged condition which may exist.

Having described my invention, I claim:

1. A device of the class described comprising a tobacco pouch formed of leather or the like, the walls of the pouch secured together along a line parallel to and relatively close to one edge of the pouch to form a long narrow compartment serving as a sheath, a pipe cleaner blade mounted in said sheath and including a handle element attached to the end of the blade opposite to the end thereof which is used, said handle element including means for attachment to a wall of the compartment when the blade is inserted in the sheath.

2. A new article of manufacture comprising a tobacco pouch formed of leather or the like and

providing adjacent side walls joined along all of the edges thereof but one, said side walls additionally joined together along a line adjacent and parallel to a side edge of the pouch providing a sheath open at one end, a pipe cleaner blade insertable into said sheath through said open end and including a thong attached to the

end opposite to its pointed end and incorporating an attaching device, said pouch including an attaching device complementary to the device on the thong and cooperating therewith for securing the blade against displacement from the sheath. 5
